BOOT AND THE LIKE

James T. Murphy, Chicago, Ill.

Application December 4, 1936, Serial No. 114,122

7 Claims. (Cl. 36—50)

This invention relates to boots and like articles and more especially to riding boots and puttees.

In riding boots as manufactured heretofore two important conflicting considerations are involved. Such boots of necessity must be as attractive as possible and at the same time must be comfortable and well fitting, but as is well known, in order for such boots to be pulled on, the calf portion must be made with a circumference substantially larger than the calf of the leg of the wearer, the consequence of which is that this portion of the boot is loose and after some use the weight of the calf portion causes a wrinkling of the leather around the ankle, all of which detracts from the appearance; and the boot being loose at the upper portion tends to discomfort and additional means of attachment as by a strap at the top is often employed.

It is to overcome these objections that my present invention has been conceived, and I have developed a boot which is not only attractive by having pleasing lines but one which is both comfortable by being form fitting and one which may be secured to the foot in a simple yet secure manner.

In my boot I have provided a slotted back portion through which the ankle and foot may be inserted, and the slit portion closed by a fastener of the well-known slide type. I have further provided partial support for the boot at the upper portion of the calf by a similar slide type arrangement on the lower portion of the trouser leg which further promotes the comfort of the wearer because of the close fit between the garment and the boot at this point. My invention is applicable not only to a boot but to a puttee and also to high-top hunting shoes having a waterproof tongue similar to those in which ordinary lacing is employed.

It is therefore an object of my invention to provide a simple, practical, and efficient article of the character described.

Another object is to provide a boot having improved and simplified securing means.

Another object is to provide a boot having a slotted portion adapted to facilitate attachment and yet having concealed attaching means.

Another object is to provide a boot having attaching means whereby the boot may conform to the ankle and calf outlines of the wearer.

A further object is to provide a boot adapted for partial support from an article of apparel, such as breeches.

Other objects and advantages will appear and

be brought out more fully from the following specification, reference being had to the accompanying drawings, in which:

Fig. 1 is a rear view of a boot illustrating my invention;

Fig. 2 is a side view of the same, partially broken away;

Fig. 3 is an enlarged detail view taken along the line 3—3 of Fig. 2;

Fig. 4 is a front view of the boot with the front portion partially broken away and showing the slotted back portion partially separated;

Fig. 5 is a fragmentary view showing the lower portion of a trouser leg with a slide attachment for connection with the boot;

Fig. 6 is a sectional view of the same taken along the line 6—6 of Fig. 5;

Fig. 7 is an enlarged detail view illustrating the slide locking means shown in Fig. 4;

Fig. 8 is a view partly in section illustrating the locking tool and a riding crop with which it may be associated;

Fig. 9 is a rear view of a boot similar to that of Figs. 1, 2, and 4, having in addition a waterproof tongue;

Fig. 10 is a partial top view of the same taken along the line 10—10 of Fig. 9; and

Fig. 11 is a front view partially broken away showing my invention as applied to a puttee.

Referring more particularly to the drawings I show a leather boot 15 having a sole 16, heel 17, upper 18, ankle portion 19, calf 20, having an upper edge 20a, and counter 21, which has a seam 22. The calf and ankle portions of the boot are slotted at the back from the top edge 20a to the counter 21 and form meeting edge

portions 23 which have meeting edges 24. A stringer 25 of hookless fasteners 26 of the well known slide type is secured along each edge portion 23 interiorly thereof as by stitching 27, 40

the stitching 27 being spaced a small amount away from the edge 24. The fasteners 26 are provided on the inner face with a locking slider 28 which has flat faces 29 and 30, the face 29 being arranged to lie along the interior of the 45

boot edge portions 23. A short section of a chain 31 is secured to the inner face 30 of slider 28 and comprises a number of balls 32 and links 33.

In order to facilitate the operation of the slider 28 I have provided an operating tool or hook 34 which has a shank portion 35 and a hook 36 which, together with a tongue 37, form an abutment notch 38, which notch is adapted to engage chain 31 whereby the slider may be pushed downwardly, the hook 36 being adapted 55

to similarly engage the chain for pulling the slider upwardly to lock the fasteners 26. The hook 34 is provided with a handle 39 which has a neck portion 40 adapted for engagement with the end of a bore 41 in the handle of a crop 42, which as shown in Fig. 8 has the usual thongs 43.

Located a substantial distance below the upper edge 20a I have provided a similar stringer 44 of 10 fasteners 45 secured as by stitches 46 circumferentially around the interior of the boot, the stringer of these fasteners being provided with a slider 47, which fasteners are adapted for attachment to a trouser leg 48 which is shown as having 15 a bottom portion 49 and buttons 50. A stringer 51 having fasteners 52 of the separable type is provided with a pin 53 which may be slipped into slider 47 for attachment of the fasteners 45 and 52. The stringer 51 is secured to the trouser leg by stitching 54. It will be apparent that 20 when applying the boot to the foot and leg the fastener connection may be made between fasteners 45 and 52, and the trouser 48 will provide partial support for the boot 15 as well as provide 25 a closed connection between the two at this point.

Referring to Fig. 11 I show my invention as applied to a puttee in which the elements numbered 19 to 26, 27, 28, 31 and 44 to 47 are substantially identical with the corresponding portions 30 of the other figures. The puttee is shown at 55 and has a top edge 56 and bottom edge 57, and a locking pin 26a is employed for separable engagement with the slider 28.

In Figs. 9 and 10 I show a boot substantially 35 similar to Figs. 1, 2, and 4, in which the slitted back opening is protected by a waterproof tongue 58 which has double folded portions 59 and edges 60 which are stitched at 61 to the meeting edge portions 23 of the boot.

While I have illustrated and described the preferred form of construction for carrying my invention into effect, this is capable of variation and modification without departing from the spirit of the invention. I, therefore, do not wish 45 to be limited to the precise details of construction set forth, but desire to avail myself of such variations and modifications as come within the scope of the appended claims.

Having thus described my invention, what I 50 claim as new and desire to secure by Letters Patent is:

1. A boot or like article having a foot portion, an ankle portion, and a calf portion, said ankle and calf portions being slitted at the back forming 55 meeting edge portions, and adjustable means to retain said meeting edges together, said means including slide type fasteners secured adjacent said meeting edges interiorly of said article, the slider of said fastener being located entirely within the article, and means for operating said slider disposed on the inside of the fasteners.

2. A boot or like article having a foot portion, an ankle portion, and a calf portion, said ankle and calf portions being slitted at the back forming 60 meeting edge portions, and adjustable means to retain said meeting edges together, said means including a stringer of slide type fasteners secured to and along each of said meeting edge portions in substantial spaced relation to said meeting edge, said meeting edges being adapted to 65 cover said fasteners and the slider when said

fastener has been actuated to the closed position, said slider being operable only from the inside of the meeting edges and inwardly of the fasteners.

3. A boot or like article having a foot portion, an ankle portion, and a calf portion, said ankle and calf portions being slitted at the back forming meeting edge portions, and adjustable means to retain said meeting edges together in abutting relation, said means including slide type fasteners secured adjacent said meeting edges interiorly of 10 said article, and actuating means for said fasteners including a slider having actuating means at the inside thereof and operable only from within the interior of the article.

4. Securing means for an article of the class 15 described having meeting edges comprising slide type fastener strips attached to said article adjacent said meeting edges and in spaced relation thereto and interiorly of said article, and an actuating slider engaging the fasteners of the fastener strips and disposed on the inside of the latter and adapted to be actuated only from within the article.

5. A boot or the like having an ankle portion and a calf portion formed to fit the wearer, said 25 ankle and calf portions being closed except at the back portion where it is slitted to form meeting edge portions, a stringer of hookless fasteners secured along the inner face of each edge portion, and an actuating slider on the inner faces of the 30 fasteners to draw said meeting edge portions together in abutting relation, said actuating slider being provided with an operating device on its inner face and operable wholly within the article and being free of all projections outwardly of 35 the article or between said edge portions.

6. As a new article of manufacture, a boot or like article having an ankle portion and a calf portion all made to conform to the outlines of the wearer, said ankle and calf portions being 40 slitted longitudinally to form meeting edge portions, stringers of fasteners secured at the inside of the article along said meeting edge portions, and a slider engaged with said fasteners and having operating means on the inner face thereof and projecting solely inwardly thereof to move and retain said meeting edges together with an uninterrupted and unobstructed smooth exterior surface free of parts between said edges and outwardly thereof.

7. A boot or like article having an ankle portion and a calf portion formed to snugly fit the wearer, said portions being slitted at the back from the top of the calf portion to the bottom of the ankle portion and forming meeting edges, stringers 55 secured along the inner faces of said portions adjacent the edges and having coacting separable fasteners, a slider engaged with the fasteners and movable along the same to draw said edges together into contact or to separate the 60 same, said slider having means on its inner face through which it may be actuated, said slider being positioned entirely within the article and the edge portions of the boot being free of portions interposed between said edges and said 65 stringers, and a tongue over the fasteners from the top to the bottom of the slit and having its opposite edges secured beyond the stringers to the inner face of said boot to enclose the stringers, fasteners and slider between said boot and tongue. 70

JAMES T. MURPHY.
